Inventor:

Fred J. Miller

United States Patent Office.

FREDERICK J. MILLER, OF BROOKLYN, NEW YORK.

Letters Patent No. 76,934, dated April 21, 1868; antedated April 10, 1868.

IMPROVEMENT IN THE CONSTRUCTION OF ICE-PITCHERS.

The Schedule referred to in these Letters Patent and making part of the same.

TO ALL TO WHOM IT MAY CONCERN:

Be it known that I, FREDERICK J. MILLER, of Brooklyn, in the county of Kings, and State of New York, have invented a new Improvement in Ice-Pitchers; and I do hereby declare the following, when taken in connection with the accompanying drawing, and the letters of reference marked thereon, to be a full, clear, and exact description of the same, and which said drawing constitutes part of this specification, and represents a section of an ice-pitcher constructed on my improved plan.

The object of my invention is to overcome an existing difficulty with the common ice-pitchers as now made by strengthening the inside bottom and wall, so that when pieces of ice are accidentally or carelessly dropped into the pitcher, the inside wall or bottom will not be bruised or pierced through, injuring the bottom and wall to such an extent that repairs are necessary, or the pitcher is useless.

To enable others to make pitchers on my improved plan, I will proceed to describe the construction of the same.

a is the outer wall, and *b* the bottom; *c* the inner wall, and *d* the inner bottom attached thereto, said bottom extending to the lower edge of the rim or foot *e*, and attached thereto, so that the lower edge of the inside bottom, *d*, will touch the table. It will now be seen that when pieces of ice are dropped into the pitcher, the force of the blow will be at *g*, and not at *f*, as is the case with the common ice-pitcher, and being supported by the table, and attached to the lower rim or foot *e*, will not tear away from the inner wall, *c*, and cause the pitcher to leak, nor will the inside bottom of the pitcher become bruised or pierced through, said bottom being made of the drum-shape, or said bottom could be made corrugated, in order to strengthen it. And it will also be seen that the strain at the point of soldering the inner wall to the top of the pitcher will be avoided. The inner bottom being soldered or attached to the lower rim, *e*, adds greatly to the strength of the rim, and entirely prevents the bruising of that portion of the pitcher.

Having thus fully described my invention, what I claim, and desire to secure by Letters Patent, is—

An ice-pitcher, having the walls *c a*, and bottoms *d b*, and lower rim or base *e*, constructed substantially as shown and for the purpose set forth

In witness whereof, I have hereunto set my signature, this 30th day of March, 1867.
